UNITED STATES PATENT OFFICE

ARTHUR E. SMITH, OF LOS ANGELES, CALIFORNIA

DESIGN FOR AN AMPUL

Application filed October 26, 1927. Serial No. 23,889. Term of patent 14 years.

To all whom it may concern:

Be it known that I, ARTHUR E. SMITH, a citizen of the United States, residing at Los Angeles, in the county of Los Angeles, and State of California, have invented a new, original, and ornamental Design for an Ampul, of which the following is a specification, reference being had to the accompanying drawing, forming a part thereof.

In the accompanying drawing Fig. 1 is an elevation of an ampul showing my new design; Fig. 2 is a top plan view thereof.

I claim:

The ornamental design for an ampul substantially as shown.

ARTHUR E. SMITH.
